UNITED STATES PATENT OFFICE.

RASCUM O. AUSTIN, OF WILKINSBURG, PENNSYLVANIA, ASSIGNOR TO WESTINGHOUSE ELECTRIC & MANUFACTURING COMPANY, A CORPORATION OF PENNSYLVANIA.

CONTROLLER.

Application filed May 10, 1922. Serial No. 559,921.

My invention relates to control systems and apparatus and it has particular relation to controllers for governing remotely-controlled switches.

5 One object of my invention is to provide a device for opening a circuit that governs a line switch, upon a slight reverse movement of a controller drum.

Another object of my invention is to provide a switching device which shall be compact and economical in construction and positive and reliable in operation.

Briefly speaking, my invention consists in providing two alined shafts with interlocking members, movably mounting a collar on one of the members to actuate a switching device and mounting a cam mechanism on the other interlocking member to actuate the collar in a direction parallel to the axis 20 of the shafts.

For a better understanding of my invention, reference may be made to the accompanying drawings,

Figure 1 of which is a view, partly in side elevation and partly in section, of a switching device mounted upon the top of a controller for governing a line switch, which is situated at some relatively remote point from the controller, in accordance with a 25 familiar practice;

Fig. 2 is a cross-sectional view, taken along the line II—II of Fig. 1 of the drawings;

Figs. 3 and 4 are views, in plan and side elevation, respectively, of the cam mechanism constituting a portion of the switching device that is illustrated in Figs. 1 and 2; and

Fig. 5 is a diagrammatic view of a control system in which a line switch attachment 40 constructed in accordance with my invention is employed.

Referring to Figs. 1 and 2 of the drawings, a controller 1, having a shaft 2, on which is mounted a plurality of cam members 3 for governing a plurality of switches 3^a, etc. (shown also in Fig. 5), has a switching device 4 constructed in accordance with my invention, mounted on top of the controller proper. The switching device 4 comprises a shaft 5, in alinement with the shaft 2 and adapted to be rotated by means of the usual handle, which has not been illustrated.

55 An interlocking member or dog 6 is se-

cured to the shaft 5 by means of a pin 6^a. The interlocking member 6 is adapted to engage a corresponding interlocking member or dog 7, which is rigidly secured to the shaft 2. A plurality of rollers 8 are rotatably mounted upon the interlocking member 6 by means of tap bolts 9. The rollers 8 are adapted to engage the adjacent contact surfaces of a collar 11 which is rotatably mounted upon the interlocking member 6. 60

The collar 11 is maintained in fixed relation to the interlocking member 7 by means of projections 12, constituting a portion thereof. The collar 11 is provided with a plurality of raised portions or flanges 13 70 and inclined surfaces 14, along which the rollers 8 are adapted to pass. The collar 11 is biased to its upper position, which is that illustrated in Figs. 1 to 4, inclusive, of the drawings, by means of a resilient member 75 or spring 15.

When the interlocking member 6 is turned in a clockwise direction, the rollers 8 will roll up the inclined surfaces 14 onto the flanges 13 of the collar 11, thereby forcing 80 the collar member 11 downwardly or towards the interlocking member 7. The downward movement of the collar 11 actuates a switching member 16, which is secured to a pivotally mounted yoke member 17. The yoke member 17 has its ends pivotally mounted upon a plurality of alined bolts 18, which are secured to the cover member 19 of the switching device 4. The cover member 19 is attached to the controller 1 90 by a plurality of tap bolts 20.

The yoke member 17 is provided with a roller 21, which rides against the under surface of the collar member 11. The yoke member 17 is biased to its upper position by 95 means of a plurality of springs 22, which are mounted on either side of the movable switch member 16. The movable switch member 16 is provided with a contact segment 23 which is adapted to engage a plurality of stationary control fingers 24 to establish a circuit which will be hereinafter more fully described. A second circuit is established within the switching device 4 upon the engagement of a stationary control finger 26 with a movable arcuate contact segment 25 which is secured to the interlocking member 7. 100 105

The operation of the switching device 4 will be more fully described after a descrip- 110

tion has been given of the control system illustrated in Fig. 5 of the drawing.

Referring to Fig. 5, a motor 31, having an armature 32 and a series field-magnet winding 33, is energized upon the closure of a line switch 35 and a ground switch 37 by a main circuit that is established from a source of electrical energy, such, for example, as a trolley 34, through the line switch 35, starting resistor 36, armature 32, series field-magnet winding 33 and ground switch 37 to a return circuit marked "Ground".

Closure of the line switch 35 is accomplished by energizing its actuating coil 15 which is effected upon the contact segment 23 bridging the stationary control fingers 24 and the movable contact member 25 engaging the stationary control finger 26. After the closure of the line switch 35, a holding circuit is provided through an auxiliary contact member 38, constituting a portion of the line switch 35, and auxiliary resistor 39 to ground. This holding circuit, when once established, is independent of the 20 relative positions of the movable contact member 25 and the stationary control finger 26.

The operation of the switching device 4 is begun by actuating the shaft 5 in a clockwise direction, when viewed from the top, until the interlocking member 6 engages the interlocking member 7 to effect the rotation of the shaft 2. The ground switch 37, which is actuated by a cam 3 of the controller 1, is closed prior to the closure of the line switch 35.

The rotation of the interlocking member 6 causes the rollers 8 to ride against the inclined surfaces 14 and the flanges 13 of the 40 collar 11, thereby forcing the collar 11 downwardly. The downward movement of the collar 11 will force the roller 21 and, hence, the yoke 17 and switch member 16, downwardly until the movable contact segment 23 engages the stationary control fingers 24. Simultaneously with the engagement of the stationary control fingers 24 by the movable contact segment 23, the 45 arcuate contact segment 25 engages the stationary control finger 26.

Upon the closure of both of these switching devices, a circuit is established from the trolley 34 through movable contact segment 23, which bridges the stationary control fingers 24, the actuating coil of the line switch 35, movable contact segment 25 and stationary control finger 26 to ground.

The line switch 35 will close when this circuit is established, and, as a holding circuit is provided through the interlocking member 38 which constitutes a portion of the line switch 35, the contact segment 25 can then pass beyond the stationary control finger 26 without causing the line switch 35 to open.

When the controller is actuated in the re-

verse direction, a slight movement of the interlocking member 6 with relation to the interlocking member 7 will cause the rollers 8 to pass down the inclined planes 14 of the collar 11, thereby permitting the spring 15 to actuate the collar 11 upwardly. When the collar 11 is actuated upwardly, the yoke member 17 will be raised by the springs 22.

The rise of the yoke member 17 will cause the movable contact segment 23 to interrupt the circuit comprising the stationary control fingers 24 and thus de-energize the actuating coil of the line switch 35. The line switch 35 will then be opened by spring 41.

From the above description, it is apparent that I have provided a novel switching device for a controller whereby the line switch will be closed subsequent to the closure of certain switches necessary to establish the main circuit of a control system and that, by means of this switching device, the line switch will be opened prior to the opening of any other main switches. This sequence of operation of the line switch and other main switches causes the line switch to interrupt the main circuits and thus its contact members will take substantially all the burning and wear that would otherwise be imposed upon the other main switches, which are not adapted for such service.

While I have shown my invention in its preferred form, it is apparent that modifications may be made in the arrangement 100 of the controller and switching device therefor without departing from the spirit of my invention and that the switching device and controller may be employed for a great number of widely different kinds of control systems. I desire, therefore, to 105 be limited only by the scope of the appended claims.

I claim as my invention:—

1. In a controller, in combination, a plurality of rotatable shafts, interlocking members carried by the shafts, said interlocking members being adapted to permit relative rotation of the shafts through a predetermined angle, a slidably mounted switch-actuating member disposed to rotate with 110 one of the interlocking members and means carried by the other interlocking member adapted to effect a sliding movement of the switch actuating member.

2. In a controller, in combination, a plurality of rotatable shafts, interlocking members carried by the shafts, said interlocking members being adapted to permit relative rotation of the shafts through a predetermined angle, a slidably mounted switch actuating member disposed to rotate with one of the interlocking members, means carried by the other interlocking member adapted to effect a sliding movement of the switch actuating member, a movable switch mem- 115 120 125 130

- ber carried by an interlocking member, and locked against angular movement relative to said switch actuating member, a second switch member disposed in a predetermined 5 position to engage the movable switch member, said switch members being disposed to engage one another substantially simultaneously with the operation of said switch actuating member as the interlocking members 10 are rotated together in a forward direction from their initial "off" position.
3. In a controller, in combination, a plurality of rotatable shafts, interlocking members adapted to permit predetermined relative angular movement carried by the shafts, a main switch member, a slidably mounted switch actuating member disposed to rotate with one of the interlocking members, and means carried by the other interlocking 15 member cooperative to give the switch actuating member a sliding movement when the interlocking members are moved relative to one another, thereby to operate the main switch member.
- 20 4. In a controller, in combination, a plurality of rotatable shafts, interlocking members carried by the shafts, adapted to permit predetermined relative angular movement, a main switch member, a slidably mounted switch actuating member disposed to rotate with one of the interlocking members, means carried by the other interlocking member cooperative to give the switch actuating 25 member a sliding movement when the interlocking members are moved relative to one another, thereby to operate the switch member, and a second switch disposed to be actuated substantially simultaneously with the main switch member.
- 30 5. In a controller, the combination with a plurality of relatively rotatable shafts, of a 35 plurality of interlocking members mounted on said shafts, a casing for said members, said members being in axial alinement and adapted to be operated the one by the other 40 for varying the distance therebetween, a yoke member pivotally mounted in opposite sides of said casing and adapted to be activated by one of said interlocking members, and a switch member carried by said yoke member. 45
6. In a controller, the combination with a plurality of relatively rotatable shafts, of a plurality of interlocking members mounted on said shafts, a casing for said members, a collar member mounted on one of said interlocking members, a yoke member adapted to be actuated by said collar and having its end pivotally mounted in said casing opposite said interlocking members, a switching device mounted on said yoke member, and means governed by the angular relation of 50 said shafts for actuating said collar.
7. In a controller, the combination with a plurality of relatively rotatable shafts, of a plurality of interlocking members mounted on said shafts, a casing for said members, a collar mounted upon one of said interlocking members, resilient means for biasing said collar to a predetermined position, means comprising a roller member on one of said 55 interlocking members for actuating said collar, a yoke member having a roller adapted to be actuated by said collar, and a switching device governed by said yoke member, the ends of the yoke member being pivotally 60 mounted in said casing at points on the opposite side of the yoke-member roller from said switching device. 65
- In testimony whereof, I have hereunto subscribed my name this 28th day of April, 1922.
- BASCUM O. AUSTIN.
